HATCH CONSTRUCTION

John T. Cralley, Chicago, Ill., assignor to P. H. Murphy Company, New Kensington, Pa., a corporation of Pennsylvania

Application July 13, 1933, Serial No. 680,201

15 Claims. (Cl. 108—5)

This invention relates to hatch constructions, particularly hatch constructions for refrigerator car roofs of the all-metal riveted-up type wherein self-supporting roof sheets extend from side to side of the car and are riveted thereto and to each other to form a rigid load sustaining structure.

The invention has for its principal objects to produce a strong, durable and simple hatch construction that can be readily incorporated in a refrigerator car roof of the above type; that will increase the strength and rigidity of the car roof and car frame; which will resist the corrosive action of briny water; and which is well adapted for economical manufacture.

The invention consists in the hatch construction and in the combinations and arrangements of parts hereinafter described and claimed.

In the accompanying drawings, which form part of this specification and wherein like symbols refer to like parts wherever they occur,

Fig. 1 is a plan view of the end portion of a metal refrigerator car roof provided with a hatch construction embodying my invention.

Fig. 2 is a vertical transverse section through the roof, the section being taken through the hatches on the line 2—2 in Fig. 1.

Fig. 3 is an enlarged fragmentary section similar to Fig. 2 through the eaves portion of the hatch plate,

Fig. 4 is a vertical longitudinal section through the roof, the section being taken through the hatch on the line 4—4 in Fig. 1.

Fig. 5 is an enlarged vertical cross-section through the end roof seam and the adjacent end of one of the combined guard rails and hatch cover supports,

Fig. 6 is a vertical longitudinal section through the roof at the ridge on the line 6—6 in Fig. 1;

Fig. 7 is a central longitudinal section through the cast metal hatch plate; and

Fig. 8 is a section similar to Fig. 4 illustrating a hatch construction of slightly modified form.

Referring to the accompanying drawings, my invention is shown in connection with a refrigerator car equipped with an all-metal, riveted-up, single-course roof construction. The body frame of the refrigerator car comprises wooden side plates 1 connected by wooden carlines 2, wooden side sheathing 3 secured to the outer face of each side plate and terminating below the top thereof, and a side fascia board 4 secured to the outer face of said side sheathing with its top substantially flush with the top of said side plate.

The metal car roof comprises self-supporting

sheets 5 of rolled steel that span the car from eaves to eaves and are rigidly connected thereto and to each other to form a rigid load-sustaining structure. The roof sheets 5 slope downwardly from the ridge to the eaves of the car and have upstanding flanges 6 along their adjacent side margins that are covered by inverted U-shaped seam caps 7 that are provided with outstanding base flanges 8 that overlie the adjacent side marginal portions of the roof sheets. The seam caps 7 are rigidly secured to the upstanding seam flanges 6 of adjacent roof sheets 5 by rivets 9 that extend horizontally through said seam caps and said seam flanges. The roof sheets 5 are provided with depending eaves flanges 10 (see 15 Fig. 1) that overhang the side fascia boards 4; and the eaves ends of the seam caps 7 are bent downwardly, as at 11, over the adjacent end portions of said eaves flanges. The roof sheets are rigidly secured near each end by rivets 12 20 to the sloping top flange of an eaves angle strip 13 whose vertical flange is bolted or otherwise rigidly secured to the outer faces of the side plates 1 above the side sheathing 3 and is offset outwardly at its lower margin so as to cover the 25 upper ends of said sheathing.

A running board extends longitudinally of the car at the ridge and preferably comprises sections 14 located between adjacent roof seams with their ends supported on the horizontal top flanges 30 of angle brackets 15 whose vertical flanges are rigidly secured to the sides of seam caps 7 by the securing rivets 9 therefor.

At the end of the car, the roof is provided with a hatch construction for admitting ice and salt 35 to the interior of the car. Said hatch construction comprises a cast metal roof plate or section 16 which slopes downwardly from ridge to eaves of the car after the manner of the rolled steel roof sheets 5. This cast metal hatch plate is 40 rigidly secured at its eaves ends to the top flanges of the eaves angles 13 by the rows of rivets 12 that secure the roof sheets to said flanges. Said hatch plate is rigidly secured along its outer margin by a row of rivets 17 to the outstanding 45 top flange of an angle 18 whose vertical flange is riveted to the upper end of the steel end 19 of the car. The cast metal hatch plate also has a rigid seam connection along its inner margin with the margin of the adjacent roof sheet, said 50 connection comprising an upstanding seam flange 20 that cooperates with the seam flange 5 of said roof sheet and a seam cap 17a which straddles said seam flange and is rigidly secured thereto by horizontal rivets 8a. The cast metal hatch plate 55

has a depending flange 21 that extends continuously along its eaves and outside margins, the portion of the flange located along the inner margin of said plate overlying the side fascia boards, 5 and the portion located along the outer margin of said plate overlapping the end angle 18. The portion of the running board that overhangs the car end is supported on and bolted to the outstanding top flange of an upstanding bracket 22 cast integral with the hatch plate at the outer 10 side margin thereof.

The hatch plate 16 is provided on each side of the running board with a hatch opening 23 that is surrounded by a continuous upstanding flange 15 24 cast integral with said plate. The upper end of said flange is provided with an inwardly extending portion that forms a seat for a cover 25 for closing the opening defined by said flange. That hatch cover is also made of cast metal 20 and is secured on one side to the flange 24 by means of hinges comprising cooperating lugs 26 and 27 cast integral with the cover and flange, respectively, and connected by a hinge pin 28. The free end of the hatch cover is provided with 25 suitable hand grabs or pockets 29; and said cover is locked in closed position by means of a locking pin 30 adapted to engage openings provided therefor in cooperating lugs 31 and 32 on the cover and flange 24, respectively. Extending between the two endmost roof seams opposite each 30 hatch opening is a metal member 33 having depending end flanges 34 that are secured to the seam caps 1 and 1a by the securing rivets therefor. These metal members serve to support the 35 hatch cover when opened; and they also serve as guard rails and as struts and tie members between the two seams.

The hatch plate 16 is provided at its outer corners with suitable roof grab irons 35 and 40 along its outer and eaves ends with series of raised ribs 36 that function as safety treads to prevent the foot from slipping. The hatch plate is provided with a plurality of spaced parallel ribs or flanges 37 that extend transversely of the roof. As shown in the drawings, these ribs 37 45 are located on the underside of the hatch plate, substantially in the plane of the portions of flanges 24 that extend transversely of the roof, and thus cooperate with said flanges to function after the manner of a beam to strengthen and stiffen the plate and increase the load carrying 50 capacity thereof. In the modification shown in Fig. 8, the flange 24a that surrounds the hatch opening is inclined upwardly and outwardly; and the ribs 37a on the underside of the plate are 55 offset with respect to the portions of said flange that extend transversely of the car.

The roof is provided with suitable insulation 38 that is attached to the wooden carlines 2, 60 and each hatch opening is lined with the usual wooden hatch frame 39 having tapering sides adapted to receive a tapered wooden plug 40 that is suspended from the hatch cover.

Among the advantages of the present hatch 65 construction are the great strength, durability and rigidity of the cast metal hatch roof plate and its great resistance to corrosive action of briny water, which accumulates thereon during the operation of passing ice and salt through the hatch openings; also, the cheapness and simplicity of the hatch construction and the facility with which it adapts itself to the application of the roof. It is particularly noted that said hatch 70 plate affords great strength in resisting stresses 75

that cause the roof and car frame to distort in service.

Obviously, the hereinbefore described arrangement admits of considerable modification without departing from the invention. Therefore, I do not wish to be limited to the precise arrangement shown and described. For instance, the hatch plate construction may be readily adapted for use with roofs of various types and, while it is preferable to make the hatch plate 10 in the form of a one-piece casting, it may be desirable, in some instances, to make the hatch plate of separate cast sections that are welded together.

What I claim is:

1. A hatch construction for railway cars comprising a cast metal plate provided with a hatch opening having a continuous flange surrounding said opening and cast integral with said cast metal plate, and a cast metal cover for said opening the free margin of said flange being provided with an inwardly extending portion forming a seat for said cover. 15

2. A hatch construction for railway cars comprising a cast metal plate adapted to extend from 25 side to side of the car and provided with a hatch opening, and a cast metal cover for said opening hinged to said flange.

3. A hatch construction for railway cars comprising a cast metal plate adapted to extend from 30 side to side of the car and provided with a plurality of hatch openings, a cast metal cover for each opening, and a hinged connection between said cover and said plate including cooperating lugs cast integral with said plate and said cover, 35 respectively.

4. A hatch construction for metal car roofs comprising a cast metal roof plate adapted to 40 span the car from side to side and provided with a hatch opening and a cast metal cover hinged to said plate for covering said opening.

5. A hatch construction for metal car roofs comprising a cast metal roof plate adapted to span the car from side to side and provided with a hatch opening and a cast metal cover hinged 45 to said plate for covering said opening, said plate having strengthening ribs cast integral therewith.

6. A hatch construction for metal car roofs comprising a cast metal roof plate adapted to 50 extend from eaves to eaves of the car and provided with a hatch opening and having continuous flanges surrounding said opening and cast integral with said cast metal plate, said plate having strengthening ribs cast integral therewith 55 that extend substantially from end to end of said plate on opposite sides of said opening.

7. A hatch construction for metal car roofs comprising a cast metal roof plate provided with a hatch opening and having a continuous flange 60 surrounding the said opening and cast integral with said cast metal plate, and a cast metal cover for said opening, said plate having strengthening ribs cast integral therewith, said ribs extending on opposite sides of said opening on the under- 65 side of said plate.

8. A hatch construction for metal car roofs comprising a cast metal roof plate provided with a hatch opening and having a continuous flange surrounding said opening and cast integral with 70 said cast metal plate, said plate having strengthening ribs cast integral therewith, said ribs extending on opposite sides of said openings on the underside of said plate, said plate being provided adjacent to said opening with a series of raised 75

- ribs cast integral with said plate that function as safety treads.
9. A hatch construction for metal car roofs comprising a cast metal roof plate provided with a hatch opening and having a continuous flange surrounding said opening and cast integral with said cast metal plate, said plate having strengthening ribs cast integral therewith, said ribs extending on opposite sides of said openings on the underside of said plate, said plate being provided adjacent to said openings with a series of raised ribs that function as safety treads, and a cast metal cover for said hatch openings having integral lugs adapted for cooperation with lugs formed integral with the flanges which surround said opening. 5
10. A hatch construction for metal refrigerator car roofs comprising a cast metal roof plate adapted to span the car from side to side and provided with a hatch opening, the inner margin of said plate being shaped for cooperation with the similarly shaped margin of an adjacent roof sheet, said plate having a depending flange cast integral therewith that extends continuously along the end and outer side margins thereof. 10
11. A hatch construction for metal refrigerator car roofs comprising a cast metal roof plate adapted to span the car from side to side and provided with a hatch opening and having a continuous flange formed integral with said plate and surrounding said opening, the inner margin of said plate being shaped for cooperation with the similarly shaped margins of an adjacent roof sheet and said plate being provided with a depending flange that extends continuously along the end and outer side margins of said plate, and a cast metal cover for said opening hingedly secured to the flanges surrounding said openings. 15
12. A hatch construction for metal refrigerator car roofs comprising a cast metal roof plate adapted to span the car from side to side and provided with a hatch opening and having a continuous flange formed integral with said plate and surrounding said opening, the inner margins of said plate being shaped for cooperation with the similarly shaped margins of an adjacent roof sheet, said plate being provided with a depending flange that extends continuously along the end and outer side margins of said plate, said plate being formed adjacent to its outer margin with an integral bracket adapted to serve as a support for a running board. 20
13. A hatch construction for metal refrigerator car roofs comprising a cast metal roof plate adapted to span the car from side to side and provided with hatch openings and having continuous flanges formed integral with said plate and surrounding said openings, the inner margin of said plate being shaped for cooperation with the similarly shaped margins of an adjacent roof sheet and said plate being arranged with a depending flange that extends continuously along the end and outer side margins of said plate, and cast metal covers for said openings hingedly secured to the flanges surrounding said openings, 25 said plate being formed with an integral bracket adapted to support the running board of the car roof. 25
14. A hatch construction for a metal car roof comprising a plurality of riveted metal roof sheets spanning the car from side to side and connected by upstanding seams, said hatch construction comprising a cast metal roof plate adapted to span the car from side to side and provided with a hatch opening, a cast metal cover for said opening hingedly secured to the plate, an upstanding seam connecting the inner margin of said roof plate to an adjacent roof sheet, and a member extending from said last mentioned seam to an adjacent seam opposite said cover and adapted to support said cover in the open position thereof. 30
15. A hatch construction for railway cars comprising a metal plate provided with a hatch opening having a continuous flange surrounding said opening, and a cover for said opening, the free margin of said flange being provided with an inwardly extending portion forming a seat for said cover. 35
